UNITED STATES PATENT OFFICE.

THOMAS S. JOHNSON, OF MORRIS, ILLINOIS.

RAILWAY-CROSSING SIGNAL.

Application filed September 10, 1924. Serial No. 736,934.

This invention relates to signaling devices for use at railway crossings to warn persons of danger from approaching trains, the purpose being to provide a simple, dependable, 5 and efficient device of this character that is fully automatic in its operation and that may be installed and maintained at relatively low cost.

Briefly stated, the improved device consists of a signal, either audible, visual or both, adapted, during approach of a train, to be operated intermittently thereby to attract attention thereto, the invention, more particularly, consisting in the provision of 15 a novel train actuated mechanism for both initiating and stopping operation of said signal.

The inventive idea is capable of embodiment in different mechanical structures, one 20 of which is shown in the accompanying drawings. It is to be understood, however, that the structure shown is merely intended as a disclosure of the invention in a certain preferred form, and that various changes 25 and desirable additions may be made in and to the same within the spirit and scope of the invention as defined in the appended claims.

In the drawings, wherein like characters 30 of reference denote corresponding parts in the different views:

Figure 1 is a plan view showing a signal and the improved mechanism for operating same;

Figure 2 is an elevation of the signal and operating mechanism therefor, as shown in Figure 1;

Figure 3 is a perspective view of the circuit closing parts of the signal operating mechanism;

Figure 4 is an elevation of the parts shown in Figure 3;

Figure 5 is a section on the line 5—5 of Figure 2; and

Figure 6 is a perspective of the circuit opening parts of the mechanism.

In the present instance, the signal forming part of the device is in the form of a sign 10 which may be of any desired design intended to attract attention, particu-

larly when it is illuminated intermittently, and, as is understood, this sign is to be located at a suitable point along a highway adjacent to its point of crossing the railway tracks indicated at 11.

An electric light bulb 12 is provided for illuminating sign 10 and, as shown, one terminal of said bulb is connected by a conductor 13 with one pole of a battery 14, while its other terminal is connected by a conductor 15 to a resilient arm 16 rising from a base 17, on which is mounted a motor 18. The upper end of arm 16 is terminated in a lateral offset 19, with which normally contacts a second resilient arm 20 also rising from the base 17, arm 20 extending across a shaft 21 geared to motor 18 and being adapted for engagement by a cam 22 on shaft 21, so that as the latter rotates, arm 20 will be moved by said cam out of contact 70 with arm 16, and when said cam passes by arm 20, the latter will spring back into contact with arm 16. Arm 20 is connected by a conductor 23 with an arm 24 secured at another location on base 17, and held by its inherent resiliency normally out of contact with another arm 25 also secured to the base.

Adjacent to arms 24—25 is mounted the mechanism for initiating operation of motor 18 and also for placing light bulb 12 in and out of circuit with battery 14, said mechanism consisting of a magnet 26 mounted on a standard or support 27 above base 17, and having cooperating therewith an armature 28, the latter including a vertically disposed arm pivoted intermediately, as at 29, to a support 30 rising from the base 17 and, below said pivot, being curved or bowed in the direction of the magnet, as clearly shown at 31, in Figures 3 and 4 of the drawings, the weight of arm 28 being so distributed that normally it falls away from magnet 26, or, if preferred, the same result may be accomplished by means of a light spring or 95 in any other suitable manner.

Mounted in a bearing 32 on the base 17 for rotation on an axis at right angles to the axis of pivot 29, is an actuator rod 33, the inner end portion of which is extended 100

upwardly, thence laterally towards bowed portion 31 of arm 28, and finally is terminated in a downwardly extending extremity 34. The outer end of this rod is extended 5 upwardly as at 35 and, adjacent to said extension 35, is provided with a cross arm 36 having a spring or springs 37 associated therewith, whereby the extension normally is maintained vertically disposed. Extension 35 is arranged in juxtaposition to tracks 11 so as to be engaged by a portion of a locomotive or car passing by the same, whereby it will be moved downwardly to rotate rod 33 and swing its inner extremity 15 34 against bowed portion 31 of armature 28, whereby the armature will be swung on its pivot 29 into effective relation to magnet 26.

Secured to base 17 is an inherently resilient arm 38 including a portion 39 that underlies the lower edge of bowed portion 31 and normally is spaced therefrom, but is adapted to contact therewith under the actuating influence of rod 33 when armature 28 is rocked on its pivot 29. Portion 39 also 25 is extended to overlie arm 24, so that the latter will be moved into contact with arm 25 upon downward movement being imparted to portion 39 by portion 31 of armature 28 after contact has been effected between parts 31 and 39.

A conductor 40 connects one terminal of magnet 26 with arm 24 and another conductor 41 connects the other terminal of said magnet through support 30, with armature 28, while a conductor 42 leads from armature 38 to motor 18 and thence to a fuse 43 and from said fuse to an arm 44, suitably mounted near the tracks 11 at a point beyond the crossing the device is intended to guard. Adjacent to arm 44 is mounted a second arm 45 maintained by its inherent resiliency normally in contact with arm 44. A conductor 46 leads from arm 45 either through conductor 13 or through a separate conductor 47 as herein shown to the same terminal of the battery to which conductor 13 is connected.

A rod 48 is mounted in a bearing 49 adjacent to arms 44, 45 and at its inner end is provided with an angularly disposed terminal portion 50 adapted to engage arm 45 and move same out of contact with arm 44 when the rod is rotated, said rod being provided at its outer end with an upstanding portion 55 51 adapted to be engaged by a portion of a train after the latter has passed the crossing whereby to rotate the rod and effect separation of the arms 44, 45. Rod 48, like rod 33, is provided with a cross arm and springs to hold its portion 51 normally in position to be struck and depressed by a portion of a passing train.

From the other terminal of battery 44, a conductor 52 leads to arm 25, from which it will be seen that when rod 33 is rotated,

as, for example, when a projecting portion on the locomotive strikes part 35 and swings same downward, contact is made between the arms 24—25 completing a circuit from battery 14 through conductor 13 to light bulb 12, from said bulb through conductor 15, arms 16, 20, conductor 23, arms 24 and 25 and conductor 52 back to the other terminal of the battery. This may be termed the light circuit. 75

At the same time the light circuit is closed, another circuit through the magnet 26 and motor 18 is also closed, said latter circuit beginning at one terminal of the battery and leading, for example, through conductor 47 to arm 45, from arm 45 to arm 44, thence through conductor 42 to the fuse 43 and motor 18 to arm 38, through arm 38 to the armature, from the armature through conductor 41 to the magnet, from the magnet through conductor 40 to arm 24, through arm 24 to arm 25 and finally to the other terminal of the battery through conductor 52. 80

As a consequence of the foregoing arrangement, whenever part 35 is tripped to effect closing of the circuits as aforementioned, the armature acts to hold arms 24, 25 in engagement, and thus maintains its own circuit as well as the light circuit and the circuit to the motor. Immediately the circuits are closed the motor begins to rotate shaft 21 with the result that cam 22 acting on arm 20 intermittently makes and breaks the light circuit causing the sign to 100 blink as is manifest. This continues until a train passes the crossing and actuates rod 48 to cause a separation of arms 44, 45, when immediately the circuit to the motor and magnet is broken and armature 28 falls 105 away from the magnet, allowing arm 24 to spring up from arm 25 and thus breaking the light circuit, whereupon the mechanism again is in normal position ready for actuation by another approaching train. 110

From the foregoing description considered in connection with the accompanying drawings, it is believed that the construction, operation and advantages of the device will be clearly understood. 115

I claim:—

A signaling device for railway crossings comprising an electrically operated signal element, a source of current connected in circuit with said element, a motor operated interrupter in the circuit connection to said element, a main control switch also included in said circuit connection, said control switch including an electro-magnet, an upstanding armature for said magnet pivoted on a horizontal axis and arranged normally to swing by gravity out of contact with the magnet core, a pivoted crank arm connected to actuate the armature in one direction and having a part in the path of 120 125 130

the wheel flanges of a moving train, a pair of contact arms one above the other and arranged to be pressed into contact with each other, means actuated by the movement of the lower end of said armature to close the circuit through said arms, one of said contact arms being connected to the source of current and the other in circuit with the

motor through the magnet and also in circuit with the interrupter and said signal element. 10

In testimony that I claim the foregoing as my own, I have hereto affixed my signature.

THOMAS S. JOHNSON.
